DESIGN FOR A HOSTESS TRAY

Margaret Lister Gay and Asa Merton Russell,
Los Angeles, Calif.

Application October 18, 1947, Serial No. 141,996

Term of patent 14 years

(Cl. D44—10)

To all whom it may concern:

Be it known that we, Margaret Lister Gay and Asa Merton Russell, citizens of the United States and residents of the city and county of Los Angeles and State of California, have invented a new, original, and ornamental Design for a Hostess Tray, of which the following is a specification, reference being had to the accompanying drawing, forming part thereof.

Fig. 1 is a perspective view of a hostess tray showing our new design.

Fig. 2 is a longitudinal section on line 2—2 of Fig. 1.

Fig. 3 is a transverse section on line 3—3 of Fig. 1.

We claim:

The ornamental design for a hostess tray, substantially as shown.

MARGARET LISTER GAY.
ASA MERTON RUSSELL.
